UNITED STATES PATENT OFFICE.

FREDERICK W. HOCHSTETTER, OF NEW YORK, N. Y., ASSIGNOR TO H. P. PATENTS AND PROCESSES COMPANY, INC., A CORPORATION OF NEW YORK.

LIGHT-REGULATOR FOR PROJECTING MOVING PICTURES.

1,301,264.

Specification of Letters Patent.

Patented Apr. 22, 1919.

Application filed December 3, 1915. Serial No. 64,861.

To all whom it may concern:

Be it known that I, FREDERICK W. HOCHSTETTER, a citizen of the United States, and a resident of New York, county and State 5 of New York, have invented certain new and useful Improvements in Light-Regulators for Projecting Moving Pictures, of which the following is a full, clear, and exact specification.

10 This invention relates to a class of devices adapted to be used in conjunction with moving picture apparatus.

My invention has for its object primarily to provide a device designed to be employed 15 particularly on a moving picture machine whereby the marginal rays of light operative on the pictures when projected will be cut-out so that only the direct rays of the light will be utilized, thus overcoming the 20 variations of light which tend to largely impair the effect of the pictures incident to the methods of projection ordinarily employed. This is accomplished mainly by providing an apertured opaque diaphragm 25 adapted to be disposed in the path of projection of the pictures of a film so that the marginal rays of light operative on the pictures will be cut-out.

30 A further object of the invention is to provide a light regulator of a simple and efficient construction, and which may be made so as to be adapted for use in conjunction with moving picture projecting machines of various types.

35 A practical embodiment of the invention is represented in the accompanying drawing forming a part of this specification in which similar characters of reference indicate corresponding parts in all the views, 40 the said invention being more fully described hereinafter, and then pointed out in the claims at the end of the description.

In the drawing, Figure 1 is a front view 45 of one form of light regulator embodying my invention.

Fig. 2 is a section taken on the line II—II of Fig. 1.

Fig. 3 is a view showing the manner in 50 which the device may be used in conjunction with a moving picture projecting machine, and

Fig. 4 is a section taken through the lens barrel of the machine showing the preferred manner of using the device.

55 The device, or light regulator has a diaphragm, or plate 10 made of metal, or any

other desired opaque material, and this diaphragm is preferably circular in shape so as to be mounted interiorly of the lens barrel, as 11, of a moving picture projecting 60 machine, as 12, of a suitable type, though this diaphragm may be of any other desired form whereby it may be effectually used by being mounted in the lens barrel, or otherwise employed in conjunction therewith. 65

Through the diaphragm 10 is an aperture 13 which is preferably substantially similar in shape to each picture of, for instance, a film, as 14, adapted to be transmitted through the projecting machines. On the 70 peripheral edge of the diaphragm 10 may be a projecting annular flange 15 serving to permit the diaphragm to be retained in a true vertical position in the lens barrel, or any other suitable means may be employed 75 for properly supporting the diaphragm for use with the machine.

When the device is employed in conjunction with a moving picture projecting machine provided with two lenses, as 16 and 80 17, in its lens barrel, the device may be disposed in the barrel back of the lens 16, as indicated, at 18, or it may be arranged in the barrel between the lenses, as at 19, or the device may be positioned in the free end of 85 the barrel, as at 20, in front of the lens 17. When only one lens is used in the barrel of the machine the device may be disposed in front, or in the back of the lens. In each instance the device is arranged so that the 90 aperture 13 of the diaphragm will be in the optical axis of the pictures when being projected, and the device is also disposed so that the annular flange 15 will preferably be in opposed relation to the lamp of the 95 machine. The rays of the light will then be directed into the annular flange so that the inner rays will pass through the aperture of the diaphragm while the outer rays of light will be cut-out by contacting with 100 the inner surface of the annular flange as well as contacting with the marginal parts of the diaphragm 10. Only the direct or inner rays of the light will thereby pass through the aperture of the diaphragm, and 105 the pictures appearing on the screen will be uniformly illuminated which in turn will sharpen as well as produce pronounced contrasts between the high lights and shadows of the photography of the images of the 110 pictures.

In the foregoing description, I have em-

bodied the preferred form of my invention, but I do not wish to be understood as limiting myself thereto, as I am aware that modifications may be made therein without departing from the principle, or sacrificing any of the advantages of this invention, therefore I reserve to myself the right to make such changes as fairly fall within the scope thereof.

Having thus described my invention, I claim as new and desire to secure by Letters Patent:—

1. The combination with a lens barrel having a lens removably secured within one end thereof by means of a bushing having an internal configuration similar to the internal configuration of the barrel inwardly of the bushing, of an apertured diaphragm having a marginal flange and removably slidably positionable at points within the

barrel inwardly of the lens or within the securing bushing at the outer side of the lens, substantially as described.

2. The combination with a lens barrel having a pair of spaced lenses removably secured within the ends thereof by means of bushings having internal configurations similar to the internal configuration of the barrel between the lenses, of an apertured diaphragm having a marginal flange and 30 slidably positionable at points within the barrel between the lenses or within the securing bushings at the outer side of either of the lenses, substantially as described.

This specification signed and witnessed 35 this second day of December A. D. 1915.

FREDERICK W. HOCHSTETTER.
